CLAIM

The ornamental design for a fluidics cart for ultrasound therapy assembly, as shown and described.

DESCRIPTION

FIG. 1 is a front perspective view of a fluidics cart for ultrasound therapy assembly in accordance with the present invention;

FIG. 2 is a left side elevation view thereof;

FIG. 3 is a right side elevation view thereof;

FIG. 4 is a front elevation view thereof;

FIG. 5 is a rear elevation view thereof;

FIG. 6 is a top plan view thereof; and,

FIG. 7 is a bottom plan view thereof.

The broken lines in the drawings depict portions of the fluidics cart for ultrasound therapy assembly that form no part of the claimed design.
